Atty.

UNITED STATES PATENT OFFICE

WILLIAM A. BATTEY, OF HAVERFORD, PENNSYLVANIA, ASSIGNOR TO PENNSYLVANIA CRUSHER COMPANY, OF NEW YORK, N. Y., A CORPORATION OF NEW YORK

CRUSHING MACHINERY

Application filed February 9, 1931. Serial No. 514,583.

My invention relates to crushing machinery of the type employing hammer-carrying rotor structures, the hammers of which engage material delivered into their path and effect 5 breakage or rupture thereof by hurling the same against a breaking surface or surfaces forming one wall or part of one wall of the crushing chamber.

In the crushing of raw material of various 10 kinds, it is common to find material containing a high moisture content, and various materials which are to be crushed, are frequently stored under such weather conditions as to absorb additional moisture.

15 In the crushing of material in a wet or moist condition, a mass of highly viscous mud builds up on the breaking surfaces and seriously impairs the capacity of the machine.

The main object of my invention therefore 20 is to provide means that will prevent this building up of a body of sticky or slimy material, mud, and/or the like, upon said breaking surface or surfaces.

Another object of my invention is to provide 25 a rocking cutting member or scraping blade arranged to be reciprocatively moved or oscillated over a breaking surface (or surfaces) against which the material is hurled by the hammers of the rotor structure.

30 And a still further object of my invention is to provide means for effecting movement of the scraping blade over said breaking surface (or surfaces).

These and other features of my invention 35 are more fully described hereinafter; reference being had to the accompanying drawing, in which:

Figure 1 is a side elevation of one form of 40 crushing structure with which the improved scraping or cleaning mechanism forming the subject of my invention may be employed, and

Fig. 2 is a sectional elevation of a portion 45 of the breaking surface; showing the scrap-

ing blade in operative position with respect thereto.

In the present instance the improved scraping means and operating mechanism therefor have been applied to a crushing 50 structure of the type illustrated in the application of George W. Borton, filed August 25, 1928, employing a hammer-carrying rotor member of usual character, arranged within a crushing chamber whose lower portion 55 is defined by a cage or screen pivotally mounted within the frame and carrying the usual bars or members with which the hammers of the rotor cooperate.

The frame of the crushing structure is indicated generally at 1, and this may have a cage or screen comprising side frames 2, pivotally mounted at 3, and carrying the usual cross-bars 4. The rotor structure may be of usual type comprising a series of disks 5, mounted on a shaft 6; said disks supporting rods 7 from which hammers 8 are hung. 60

The end wall of the frame carrying the breaking surface may be curved, as clearly indicated in Fig. 2, and this surface, indicated 70 at 9, preferably carries a series of wear plates 9^a, suitably secured in place and renewable when worn. The material to be crushed is fed through the usual chute or hopper opening at the upper portion of the frame and is 75 hurled against the breaking surface (or surfaces) and partly broken by impact thereon; further breaking or reduction being effected by the hammers 8 cooperating with the cross-bars 4 of the cage or screen. 80

When material carrying a large moisture content is being reduced, considerable difficulty is had in keeping the breaking surface clean. In practice, a wall of mud builds up on such breaking surface, and such wall 85 being so much less hard than the normal breaking surface, there is practically no breaking by impact, and unless removed, the breaker plate will become clogged with mud and destroy the efficiency of the machine and, 90

in some instances, stop the operation of the same.

To overcome the difficulty occasioned by the wet or damp portion of the material building up on the breaking surface, I propose to employ a scraping bar or blade 10, more clearly shown in sectional view, Fig. 2, which blade is reciprocatively movable over the breaking surface 9. This blade is provided with trunnions 11 at its ends, which are adapted to pass through slots 12 formed in the side walls of the crusher frame, such trunnions being pivotally connected at 11^a to swinging arms 13, which in turn are pivotally connected at 13^a to the side walls of the crushing structure, and arranged on both sides of the same. If desired, the pivotal connection 13^a for the arms 13 may be in the form of a cross-bar or shaft extending from side to side of the frame of the crushing structure.

The arms 13 are preferably curved, as indicated in Fig. 1, so as to clear projecting portions of the side frames, and one of these arms may be extended, as indicated at 14, and connected by means of a link 15, to a crank arm 16, on the end of a shaft 17, connected to gear-reducing means which may be disposed in a casing 18, and operatively connected to and driven by a suitable motor 19.

The slots 12 formed in the side walls of the crusher frame are on the arc of a circle struck from the axis of the pivotal connection 13^a for the arms 13, and they may be provided with guideways 20 for engagement by slide-blocks carried at the ends of the scraping blade 10 and interposed between the trunnions of the latter and said arms 13.

While I have shown a curved breaking surface (or surfaces) engaged by the scraping or cutting blade 10, it will be understood that my improved operating mechanism which serves to reciprocate or oscillate said blade over such breaking surface (or surfaces) may be employed with a cutting or scraping blade arranged for straight line movement; suitable links being interposed between the blade and the pivoted operating arms 13, or provision for lost motion made, so that oscillation of said pivoted arms may effect straight line movement of the scraping or cutting blade.

I claim:

1. The combination, in crushing machinery of the rotary beater type, of a casing or frame having a curved breaking surface, a scraping blade disposed within said casing and having end connecting portions; the walls of said casing having curved slots for the passage of said end connecting portions, arms pivotally connected at one end to the casing and at the opposite end to said scraping blade, and means for moving said arms

whereby said scraping blade may be swung across the curved breaking surface.

2. The combination, in crushing machinery of the rotary beater type, of a casing or frame having a curved breaking surface and slots in its side walls adjacent to said breaking surface, a scraping blade disposed within said casing and having end connecting portions passing through said slots, arms pivotally connected at one end to the casing and at the opposite end to projecting ends of said scraping blade, and means for moving said arms whereby said scraping blade may be swung across the curved breaking surface in cleaning contact therewith.

In witness whereof I have signed this specification.

WILLIAM A. BATTEY.
